UNITED STATES PATENT OFFICE

EDWARD C. NEWTON, OF LOS ANGELES, CALIFORNIA

TIMER FOR IGNITION SYSTEMS

Application filed December 7, 1926. Serial No. 153,050.

This invention relates to improvements in timers for ignition systems, and more particularly to the contacts, or commutators of ignition governors, such as is shown and described in a pending application filed by me on the second day of May 1923 and serially numbered 636,051.

Commutators as now constructed and as shown in the recited application comprise 10 contact plates and terminals "built in" a shell or casing, and are commonly imbedded in the shell or casing at the time of its formation by molding out of insulating material such as bakelite.

15 All such plates, or commutator segments are constructed of relatively soft metal such as brass, or copper, and are therefore subject to deterioration by wear from a wiper, or movable contact and as a consequence their 20 replacement, when no longer serviceable, requires an entire new shell, or casing, with its fixed, built in, contact plates, or commutator segments.

An object of my present invention is to 25 provide supplementary contact plates, or commutator segments, which may be readily attached, or detached, that is, both physically and electrically connected with the fixed, built in, plates of the shell of the timer, and 30 to thereby extend, or prolong the life and service of the timer, as a whole.

A further object of the invention is to provide a supplementary contact plate, the parts of which can be readily stamped out by dies 35 and which is so constructed that when worn it may be reversely attached to expose the face thereof which has not been worn, thus doubling the life of the device.

40 My improvements consist in the novel construction, arrangement and combination of parts as hereinafter fully, clearly and concisely described, definitely pointed out in my claims and illustrated by the accompanying drawing, (1 sheet) in which:—

45 Fig. 1 is an inside face view of the shell, or casing, of an ignition timing device, and supplementary commutator constructed in accordance with my invention, with the timer shaft and wiper removed.

50 Fig. 2 is a sectional elevation taken on the

line indicated 2—2 of Fig. 1, and showing by dotted lines the timer shaft and wiper.

Fig. 3 is a face view of the supplementary contact plates, and

Fig. 4 is a sectional elevation taken on the 55 line indicated 4—4 of Fig. 3.

Referring more specifically to the drawing A designates the timer casing, which is a unitary, integral structure, formed of insulating material, preferably "bakelite" and formed by molding and in the form shown is of bowl shape and comprises a circular side wall B and a substantially flat end, or bottom wall C.

55 Embedded in the wall C of the casing, at uniformly circumferentially spaced intervals are the fixed metallic contact plates D which lie on a common plane flush with the inner surface of the wall C, and imbedded in the wall B are the integral extensions E of the plates D. Extended through the wall B and secured therein by threading into bores formed therethrough are the screws F which are electrically connected with the extensions E and provide terminals for conductors leading away from the commutator, as from 70 spark plugs. As is common each screw F is locked in place as by a lock-nut G and furnished with a binding nut H for conductors, or wires.

75 The shell, shown, is arranged for securement to the wall of an internal combustion engine about a timer shaft I (shown only by dotted lines in Fig. 2) and is provided with means such as the seat J (Fig. 2) for securing to the engine wall as by a clamp, not shown.

80 Each of the plates D, in its body portion, is of a shape, except for its extension F by preference, identical with the supplemental 85 plates 5 as shown in Figs. 1 and 3, and as shown in Fig. 2, has an internally threaded seat K.

85 The plates 5 referred to, are formed, preferably, as stampings from sheet material, 90 possessing electrical conductivity, such as sheet brass, and in each is a countersink 6, and as shown are secured in a carrier, such as the disc, or plate, 7, of insulating material, 95 preferably "bakelite" and formed as a mold- 100

ing, in identical arrangement as and for, registration with the described fixed plates, D. The carrier 7, with its plates 5 are secured in place as by screws 8 extended through the countersinks 6 and seated in the threaded 5 seat K of the plates D.

As best shown in Fig. 4. I prefer to provide the carrier, or disc, 7 with the plates 5 on one face and identically similar plates 5' on the opposite face, to the end that a timer 10 equipped with such plates 5 and 5' constituting supplementary commutator segments, will have its original service life (in the plates D which ordinarily constitute commutator 15 segments) plus the lives of the supplementary commutator segments in the removable and replaceable carrier.

With the wiper element, or movable contact, as is common being removable and replaceable, and the shell or casing, and wiper carrier being practically indestructible or susceptible to being rendered unserviceable 20 I, by the provision of renewable commutator segments, produce a timer that will have indefinite life, and which will result in great 25 economy of operation.

I claim:—

1. A device of the class described comprising a substantially disc-shaped body of insulating material, a series of contact plates carried at each face of the body which are relatively insulated of similar shape and attached opposite to each other, there being registering openings through the plates and 35 the insulation therebetween for the reception of securing means for the device.

2. A device embodying a flat wall of the class described, comprising a casing of insulating material having fixed metal segments radially positioned therein on a common plane, a reversible commutator adapted 40 to fit within said casing, commutator segments on each side of said commutator, and means for electrically connecting said reversible commutator segments to each of said fixed metal segments.

In testimony I have affixed my signature.

EDWARD C. NEWTON.
